UNITED STATES PATENT OFFICE.

RICHARD J. SCHULZE, OF BROOKLYN, NEW YORK, ASSIGNOR TO SAART BROTHERS COMPANY, A CORPORATION OF RHODE ISLAND.

DESIGN FOR HAND MIRROR OR SIMILAR ARTICLE.

Application filed January 9, 1924. Serial No. 8,283. Term of patent 7 years.

To all whom it may concern:

Be it known that I, RICHARD J. SCHULZE, a citizen of the United States, residing at New York, in the county of Kings and State of New York, have invented a certain new, original, and ornamental Design for a Hand Mirror or Similar Article, of which the following is a specification, reference being had to the accompanying drawings, forming a part thereof.

Figures 1 and 2 are a side elevation, and a rear elevation respectively of a hand mirror or similar article embodying my invention.

I claim:—

The ornamental design for a hand mirror or similar article as shown.

RICHARD J. SCHULZE.
